(57) **CLAIM**

The ornamental design for a ball mount clamp, as shown and described.

DESCRIPTION

FIG. 1 is a top perspective view of a ball mount clamp showing an embodiment of my new design;

FIG. 2 is a first side view thereof;

FIG. 3 is a second side view thereof;

FIG. 4 is a top view thereof;

FIG. 5 is a bottom view thereof;

FIG. 6 is an end view thereof;

FIG. 7 is a top perspective view of a ball mount clamp showing another embodiment of my new design;

FIG. 8 is a first side view thereof;

FIG. 9 is a second side view thereof;

FIG. 10 is a top view thereof;

FIG. 11 is a bottom view thereof; and,

FIG. 12 is an end view thereof.

(Continued)

The broken lines in the drawings are included to show portions of the ball mount clamp that form no part of the claimed design.

1 Claim, 6 Drawing Sheets
